(57) **CLAIM**

The ornamental design for a ring cutter as shown and described.

DESCRIPTION

FIG. 1 is a front perspective view of a ring cutter showing my new design in accordance with a first embodiment;

FIG. 2 is a rear perspective view thereof;

FIG. 3 is a front view thereof;

FIG. 4 is a rear view thereof;

FIG. 5 is a right view thereof;

FIG. 6 is a left view thereof;

FIG. 7 is a top view thereof; and,

FIG. 8 is a bottom view thereof.

Portions of the ring cutter depicted in broken lines forms no part of the design.
